PRIMARY VOTING MECHANISM

Alvin N. Gustavson, Jamestown, N. Y., assignor
to Automatic Voting Machine Corporation, a
corporation of Delaware

Application July 7, 1936, Serial No. 89,341

3 Claims. (Cl. 235—55)

This invention relates to an improvement in voting machines and more particularly to the provision of a party lever therefore.

All voting machines are necessarily provided with some means for voting a straight party ticket. In the majority of machines a party lever, located adjacent one end of a party row of vote indicators, is provided for this purpose. This lever is adapted to increase the speed of party voting by actuating all indicators in a party row and eliminating the necessity of individual manipulation of each candidate indicator. Due to the fact that a great number of voters fail to understand the simple use of voting machines and attempt to cast votes in a manner contrary to specific instructions, voting machines today, although provided with many safety devices for the prevention of erroneous voting, are constantly subjected to misuse and structural abuse. Misuse generally occurs when a voter attempts to force a locked candidate indicator or party lever into voting position after having improperly manipulated other indicators or another party lever.

The present invention is directed to the provision of means by which to prevent damage to the mechanism of a voting machine through improper use of a party lever. In order to actuate all candidate indicators in a party row through the use of a party lever, said lever must be considerably larger, stronger, and have greater leverage than any of the candidate indicators. Consequently, when a voter attempts to improperly manipulate a party lever, due to the size thereof, sufficient leverage is provided by which he may damage or break that part of the mechanism of the voting machine which is locked against voting. This occurs either by prior set up of the machine or erroneous manipulation of individual indicators thereon. To prevent this, applicant provides a party lever which may be manipulated under any and all circumstances and yet will only actuate a party row of indicators when said indicators are released and the party vote is being properly cast.

One of the objects of the invention lies in the provision of a party lever which will simultaneously actuate candidate indicators in a party row for the purpose of enabling a voter to quickly and easily cast a straight party ballot.

Another object of the invention lies in the provision of a party lever which may be actuated by a voter without actuating the party row indicators, when any indicators in another party row have previously been actuated.

Another object of the invention lies in the provision of means for connecting a party lever with a party bar, the means being yieldable and serving to absorb movement of the party lever instead of transmitting this movement to the party indicators when said indicators are locked by erroneous balloting on the part of a voter.

Other and further objects of the invention will be more fully understood from a consideration of the following specification taken in conjunction with the accompanying drawing and in which

Fig. 1 is a fragmentary front elevation of a voting machine showing a party lever and several candidate indicators in a party row;

Fig. 2 is a horizontal sectional view taken substantially on the line 2—2 of Figure 1 and shows connection of the party lever with the party bar and candidate indicators;

Fig. 3 is a view similar to Figure 2 and shows the party lever manipulated when the party bar is locked against movement;

Fig. 4 is a rear view of the party lever showing the interior structure thereof; and

Fig. 5 is a vertical sectional view taken substantially on the line 5—5 of Figure 4 and shows the pivotal support for the lever.

Referring to the drawing, the reference numeral 10 is employed to generally indicate a portion of the face of a voting machine, embodying one form of this invention. Secured to the face of the machine is a guide 11 in which is located a candidate strip 12. Directly above each candidate's name is located a candidate indicator 13 which is mounted in any suitable manner on the machine. A shaft 14, forming a part of the indicator 13, is fitted with an arm 15. The arm 15 supports one end of an interlocking strap 16, and is also provided with a lug 17 which may engage a slidable bar 19. This bar is known as the party bar and has connection with a lug 17 on each indicator in a party row and, under certain conditions, is adapted to be moved to actuate all candidate indicators in the party row. The bar is mounted for lateral movement on the rear face of the machine in any suitable manner not shown, as for example, by the provision of pins on the machine projecting through slots in the bar. Inasmuch as the type of indicator and the specific means of connecting the indicator arm with the party bar forms no part of the invention, further description thereof is believed unnecessary.

Secured in any suitable manner to the face of the machine, adjacent the row of indicators 13, 55

is a bracket 20. This bracket is generally U-shaped and formed with an opening 21 in the base wall 22 thereof, the opening coinciding with an opening 23 in the front wall of the machine. 5
 5. A party lever 25 is mounted for pivotal movement on the bracket 20. This lever is generally channel shaped and terminates at its free end 26 in a reinforced portion to which a knob 27 is suitably secured. The front face 28 or base wall 10
 10 of the channel shaped lever, is made with a slot 30 through which a card bearing the party name may be visible. This card is held in place in any suitable manner, as by a spring plate 31, which conforms to the contour of the wall 28 and is secured 15
 15 at one end by a rivet 32. Substantially midway of the ends of the lever is a pin 33, which terminates in the top and bottom walls thereof. It will be noted that the top and bottom walls of the lever increase in width from the knob 27 to 20
 20 the other end to provide a compartment 34 for a plate 35. A bushing 36 is located in the compartment 34, being secured to the upper and lower walls thereof. A shaft 37 secured to the side walls of the bracket 20 projects through the bushing 36 and mounts the lever 25 for pivotal movement in a horizontal plane. On the bushing 36 is a spacer 39. Encircling the spacer is a coiled spring 40 having a terminal 41 engaged with pin 33 and a further terminal 43 projecting into an 25
 25 opening provided therefore in the plate 35. It is to be noted that the spring 40 encircles the spacer 39 in a clockwise manner. The plate 35 is made with an opening 44 through which bushing 36 projects to support said plate for pivotal movement with respect to the lever 25. Referring to Figure 5, it will be noted that spacer 39 and plate 35 occupy the space between the top and bottom walls of the channel shaped lever 25. An arm 46 projects from an edge of the plate 35 and is 30
 30 caused by tension of spring 40 to contact pin 33 on the side opposite from terminal 41 of said spring. The plate 35 is provided with a finger 47 which projects through opening 21 of bracket 20 and opening 23 of the front wall of the machine. 35
 45. The party bar 19, is formed with an opening 48 in which to receive the finger 47 of plate 35. For a full understanding of the operation of the invention it is assumed that a voter desires to cast a straight party ballot, and that said voter 50 has not manipulated any other party lever or any indicators. The voter grasps knob 27 and swings the lever outwardly from the face of the machine to the position shown in Figure 3, wherein the walls of the lever contact the face of the machine 55 and act as a stop to further pivotal movement. The only connection between the party lever 25 and plate 35 is through spring 40, and since the tension of this spring is greater than any friction of party bar 19 and the candidate indicators connected therewith, said spring will cause plate 35 to pivot with lever 25. Consequently, the finger 47 will move party bar 19, and said bar will in turn move candidate indicators 13 into voted position. The spring 40 normally urges arm 46 60 into contact with pin 34 and, thus when lever 25 is returned to non-voting position, plate 35 will rotate about pin 37 as one with the party lever. 65
 65. It is now to be assumed that a voter has erroneously manipulated one or more indicators in another party row or another party lever, and 70

then desires to vote a straight party ticket by manipulating the party lever 25. As heretofore explained, all voting machines are provided with locking devices which prevent improper voting, and inasmuch as the voter in question has already cast a ballot in another party, he is not entitled to vote another straight party ticket, since some of the candidates would thereby receive two votes. However, not knowing that this cannot be done, he manipulates the party lever 10 25. In this instance, the party bar 19 locks plate 35 against rotation through engagement with finger 47. The party lever, however, being engaged with plate 35 only through spring 40, may be moved to the position shown in Figure 3 and 15 spring 40 will take up this movement, this figure showing the position of the party lever under these conditions. It will be understood that sufficient force could be applied to move the party bar 19 and actuate indicators 13 even though 20 they were locked, but that this would result in damage to the locking mechanism as well as other parts of the machine. The tension of spring 40, therefore, is only sufficient to cause plate 35 to rotate as one with lever 25 to overcome 25 the ordinary friction involved in moving party bar 19 and indicators 13, but the tension of said spring is insufficient to move said bar and indicators when they are locked against movement.

Although applicant has shown and described 30 only one modification of the invention, it will be apparent to those skilled in the art that other modifications or adaptations of a lever for a voting machine may be made without departing from the spirit and scope of the invention as defined in the hereunto annexed claims.

Having thus set forth my invention what I claim as new and for which I desire protection by Letters Patent is:—

1. In a voting machine having a horizontally 40 arranged row of candidate indicators, a lever mounted for pivotal movement on said machine adjacent said row of indicators, a bar connected with and adapted to actuate said indicators, pivotal means engaged with and adapted to actuate said bar, said pivotal means having yieldable 45 connection with said lever and serving to prevent transmission of movement of said lever to said bar under predetermined conditions.

2. In a voting machine having a horizontally 50 arranged row of candidate indicators, a lever mounted for pivotal movement on said machine, a bar connected with and adapted to actuate said indicators, and means yieldingly connecting said lever with said bar, said means being adapted to absorb movement of said lever and prevent forced movement of said bar and said indicators when said indicators are locked.

3. In a voting machine having a horizontally 60 arranged row of candidate indicators, a lever, a bracket on the face of said machine mounting said lever for pivotal movement, a bar connected with and adapted to actuate said indicators, means in said lever connected with said bar, said means having spring connection with said lever whereby movement of said lever may be absorbed 65 to prevent forced movement of said bar and said indicators when said indicators are locked.

ALVIN N. GUSTAVSON.
